RECORDING DEVICE

Frank L. Pankau, Milwaukee, Wis.

Application August 4, 1936, Serial No. 94,225

2 Claims. (Cl. 281—6)

My invention relates to recording devices, and more particularly to a type of device that may be employed by housewives to indicate requirements of dairy products or other supplies.

5 The object of my invention is to provide a device of the character described that may be constructed of cardboard, light metal, or the like, so as to provide a device applicable for the purpose intended, that may be distributed among 10 consumers at a nominal price.

Another object of my invention is to provide a device of the character described that may be designed to incorporate a yearly record, if desired, yet permitting a weekly or monthly statement to 15 be removed without affecting the remainder of the record.

It is manifest to any one familiar with the art of consumer distribution that a daily record of requirements is very desirable. It is also imperative that such a record be displayed in a convenient location so that the delivery salesman 20 may have access to it.

My device, as described, will permit a record for as long a period as one may desire, to be rolled into an enclosure and to be extended outwardly by degrees as far as desired. A graduated guide at all times registers the record on the recording chart and also acts as a cutting edge when a part of the record is removed.

30 Other and incidental objects not particularly mentioned in the foregoing will be apparent during the course of the following description.

In the accompanying drawing forming a part of the specification

35 Fig. 1 is a plan view of the device.

Fig. 2 is a cross sectional view of the device taken at line AA of Figure 1.

Fig. 3 is a perspective view of the device, and

40 Fig. 4 is a fragmentary cross sectional view of the chart rolled onto a revolving reel inside of a protecting housing.

Referring to the drawing in detail wherein like characters of reference denote corresponding parts, the reference character 11 shows a base on 45 which is mounted a cover plate. This cover plate has a cylindrically formed section 12 disposed to cover a chart 13 mounted on a reel 14 which reel is horizontally disposed and centrally supported by flanged members 15. There are side discs 16 50 employed by the user for revolving the reel and being of somewhat larger diameter than the section 12, they guide the record 13 on the reel 14 preventing side play while revolving. The cylindrical section 12 terminates into a flat member 17 mounted adherently or by means of rivets or the like to the base plate 11. This flat member 17 provides a suitable space for display adver-

tising and an aperture 18 through both the members 17 and 11 at a place near the outer margin permits hanging the device onto a wall or the like.

Opposite from the flat member 17 on the cylindrical section 12 is an indexing member 19 graduated and ruled to conform with the rulings on the chart 13 as shown. The indicating member 19 is fastened to the base 11 on its outer edges at 20 and 20' only, thereby permitting the chart 13 to 10 pass between the member 19 and the base 11 as it is unrolled from the reel 14, and the depending edge 21 of the member 19 may be employed as a cutting edge when tearing off a section of the chart 13. 15

The chart 13 may be ruled or arranged in any desirable manner and the indicating member 19 is to be graduated to correspond with the chart 13. In the illustration of Figure 1 the index and record chart refer to dairy supplies such as milk, 20 cream, or butter, but any other commodity may be charted. By arranging the lines according to the days and months, a monthly record may be detached from the rolled chart without affecting the remainder of the chart. The chart applied 25 to the reel is protected at all times by the cylindrical section 12 and may be rolled off or on by means of the user turning the side discs.

The invention is susceptible to various changes in its form and minor details of construction and 30 the right is herein reserved to make such changes as properly fall within the scope of the appended claims.

Having thus described my invention what I 35 claim and desire to secure by Letters Patent in the United States, is:

1. A device of the character described comprising in combination a base plate, an attached cover plate, said cover plate constructed shorter than said base plate and formed to provide a 40 cylindrical enclosure equipped with oppositely extending ends, said cover attached to the base plate near its outer edge to permit free and slide- 45 able movement of paper between said cover and base plate when a reel of paper is inserted into the cylindrical enclosure of said cover plate.

2. A device of the character described comprising in combination a flat base plate, a cover plate of substantially the same width as said base plate, said cover plate formed to provide a 50 cylindrical enclosure having projecting ends, said ends fastened to said base plate at its outer edges thereby permitting the end of a reel of paper to be slidably accessible when mounted into said cylindrical enclosure. 55

FRANK L. PANKAU.
